Application December 22, 1950, Serial No. 202,214
In Germany January 29, 1949

20 Claims. (Cl. 200—48)

1

The present invention relates to disconnecting or insulating switches, and more particularly to disconnecting switches for high voltage installations.

The present invention is intended in the first line for open air installations. However, it should be understood that the present invention is not limited to disconnecting switches for open air installations but can also be used for installations located indoors.

It is an object of the present invention to provide a disconnecting switch having contacts capable of carrying high current intensities such as short circuit currents.

It is another object of the present invention to design the contacts in a simple and well-arranged manner.

It is a further object of the present invention to render the disconnecting switch resistant against the weather particularly rain and ice formation, dust or acidic vapors.

It is a still further object of the present invention to provide a disconnecting switch which has a high contact pressure in the closing position thereof.

It is still another object of the present invention to provide a disconnecting switch in which the contact pieces slide on each other during the closing motion of the switch so that the contact pieces are freed of dust or ice which may have formed as a deposit thereon.

A disconnecting switch according to the present invention consists in a disconnecting switch for high voltage installations, comprising in combination, a pair of movable arms, contact pieces arranged on the arms, respectively, the contact pieces being arranged with respect to each other for engagement at a predetermined relative position of the movable arms, the contact pieces being rotatable about the axes of the arms, respectively, and resilient means opposing the rotation of the contact pieces after engagement thereof.

Preferably the movable arms are hollow and the resilient means are arranged inside the arms and connected to the contact pieces so as to oppose the rotation of the contact pieces after engagement thereof.

A preferred embodiment of the present invention comprises in combination, a pair of swingable hollow arms, contact pieces rotatably connected to the arms, respectively, the contact pieces being arranged with respect to each other for engagement at a predetermined relative position, each of the contact pieces including a pair

2

of differently shaped contacts, the contact pieces being rotatable after engagement thereof about the axes of the arms, respectively, the differently shaped contacts describing arcs of different lengths about the axes of the arms during the rotation of the contact pieces, and resilient means arranged inside the arms and connected to the contact pieces so as to oppose the rotation of the contact pieces after engagement thereof.

Preferably the differently shaped contacts are a hook-shaped contact and a substantially rod-shaped contact having a length in the axial direction of the contact piece which is appreciably longer than the axial length of the hook-shaped contact, whereby the rod-shaped contact of one of the contact pieces engages a leg of the hook-shaped contact of the other of the contact pieces and vice versa.

Preferably the resilient means are designed as torsion springs.

Preferably flexible current leads are connected to the arms, respectively.

In a preferred embodiment of the present invention the pair of tubular arms is arranged for pivotal motion about parallel axes, respectively, and the contact pieces come into engagement when the tubular arms are moved about the axes thereof, respectively, into substantial alignment with each other.

A preferred embodiment of the present invention comprises a pair of parallel stationary members arranged at a distance apart from each other and a pair of ball bearings connecting the stationary members and the tubular arms, respectively.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a perspective side elevation partly in section of a disconnecting switch according to the invention;

Fig. 2 is a plan view of the outer ends of the arms carrying the contact pieces in a position in which the latter just engage each other.

Referring now to the drawings and first to Fig. 1, the disconnecting switch is mounted on top of two insulators 10 arranged parallel and at a distance apart from each other, and com-

prises two equal parts, one of which is shown in the left half and the other one of which is shown in the right half of Fig. 1.

On top of each insulator 10 is pivotally mounted a head 12 having a horizontal boring for the reception of an arm 14 and a vertical boring for the reception of the stationary connecting member 16 which is connected to the head by means of a ball bearing 18. By this arrangement the head 12 can be rotated about the vertical axis thereof while the stationary connecting member 16 remains at rest, thus forming an axis of rotation for the pivotal motion of the associated arm. A flexible current lead 20 connects the stationary connecting member 16 with the arm 14 near the pivot thereof.

The arms 14 are designed as tubular members in which resilient means such as torsion springs 22, only one of which is shown in Fig. 1, are arranged which are connected at one end thereof to clamping pieces such as 24 arranged at the end of the tubular arms 14 in the heads 12 where they are kept in position by means of set screws such as 26.

The other ends of the arms 14 are connected to contact pieces 28 so as to be rotatable about the axes of said arms, respectively, to which the other ends of the torsion springs 22 are rigidly connected, respectively. Each contact piece 28 includes a hook-shaped contact 30 and a substantially rod-shaped contact 32 having a length in the axial direction of the contact piece 28 which is appreciably longer than the axial length of the hook-shaped contact 30. A set screw such as 34 arranged in the head 12 and a slot of the tubular arm 14 limits the rotation about the axis thereof.

The operation of this device is as follows:

When the switch is in the open position the tubular arms 14 are turned by the torsion springs 22 in the direction indicated by the arrows 36 until the tubular arms 14 are arrested by the set screws 34, the torsion springs 22 being in this position slightly tensioned.

If the switch is to be closed the arms 14 are swung about the vertical axis of the stationary member 16 until they are in substantial alignment with each other. During the beginning of the last part of this movement the contact pieces 28 come into engagement with each other as shown in Fig. 2 when the axis 40 of the arms 14 include angle α with the line 42 connecting the pivots thereof. If the tubular arms 14 now move further on until they are in exact alignment with each other the arms rotate about the axes thereof in directions opposite to those indicated by the arrows 36 until the set screws 34 limit these rotations.

In consequence thereof the rod-shaped contact 32 of one contact piece which came into engagement with the leg of the hook-shaped contact 30 of the other contact piece exerts a relatively high contact pressure on the hook-shaped contact 30, the rod-shaped contact 32 traversing a longer circular arc than the leg of the hook-shaped contact 30 engaged by the same. During this motion the arms are moved about their pivots, respectively, through the angles α shown in Fig. 2. The contacts displace each other by a distance x (Fig. 2) opposite to the direction of the arrows 36, this distance controlling the magnitude of the spring action and thus the contact pressure. Thus it will be seen that in the closed position of the switch a contact pressure acting in the direction

of the arrows 36 is obtained which is much larger than the contact pressure obtainable with the devices hitherto known. The high contact pressure guarantees a good contact and secures the lifting of any ice cover which may have formed itself on the relatively narrow contacts.

The flexible current leads 20 are so arranged that they do not impede the swinging movements of the arms 14 and the rotating movements about the axes thereof. Ice formed on the flexible current leads 20 cannot cause any disturbance.

The ball bearings 18 safeguard an easy actuation of the arms 14 even under unfavorable atmospheric conditions.

It will be understood that each of the elements described above, or two or more together, may also find a useful application in other types of disconnecting switches differing from the types described above.

While I have illustrated and described the invention as embodied in a disconnecting switch for high voltage installations, I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What I claim as new and desire to secure by Letters Patent is:

1. A disconnecting switch for high voltage installations, comprising in combination, a pair of movable arms; contact pieces arranged on said arms, respectively, said contact pieces being arranged with respect to each other for engagement at a predetermined relative position of said movable arms, said contact pieces being rotatable about the axes of said arms, respectively; and resilient means opposing the rotation of said contact pieces after engagement thereof.

2. A disconnecting switch for high voltage installations, comprising in combination, a pair of movable hollow arms; contact pieces arranged on said arms, respectively, said contact pieces being arranged with respect to each other for engagement at a predetermined relative position of said movable arms, said contact pieces being rotatable about the axes of said arms, respectively; and resilient means arranged inside said arms and connected to said contact pieces so as to oppose the rotation of said contact pieces after engagement thereof.

3. A disconnecting switch for high voltage installations, comprising in combination, a pair of swingable hollow arms; contact pieces connected to said arms, respectively, so as to be rotatable about the axes of said arms, said contact pieces being arranged with respect to each other for engagement at a predetermined relative position of said swingable arms, said contact pieces being rotated after engagement thereof about the axes of said arms, respectively; and resilient means arranged inside said arms and connected to said contact pieces so as to oppose the rotation of said contact pieces after engagement thereof.

4. A disconnecting switch for high voltage installations, comprising in combination, a pair of

swingable hollow arms; contact pieces connected to said arms, respectively, so as to be rotatable about the axes of said arms, said contact pieces being arranged with respect to each other for engagement at a predetermined relative position, each of said contact pieces including a pair of differently shaped contacts, said contact pieces being rotated after engagement thereof about the axes of said arms, respectively, said differently shaped contacts describing arcs of different lengths about the axes of said arms during the rotation of said contact pieces; and resilient means arranged inside said arms and connected to said contact pieces so as to oppose the rotation of said contact pieces after engagement thereof.

5. A disconnecting switch for high voltage installations, comprising in combination, a pair of swingable hollow arms; contact pieces connected to said arms, respectively, so as to be rotatable about the axes of said arms, said contact pieces being arranged with respect to each other for engagement at a predetermined relative position, each of said contact pieces including a hook-shaped contact and a substantially rod-shaped contact having a length in the axial direction of said contact piece which is appreciably longer than the axial length of said hook-shaped contact, said contact pieces being rotated after engagement thereof about the axes of said arms, respectively, whereby said rod-shaped contact of one of said contact pieces engages one leg of said hook-shaped contact of the other of said contact pieces, and vice versa; and torsion springs arranged inside said arms and connected to said contact pieces so as to oppose the rotation of said contact pieces after engagement thereof.

6. A disconnecting switch for high voltage installations, comprising in combination, a pair of swingable hollow arms; contact pieces connected to said arms, respectively, so as to be rotatable about the axes of said arms, said contact pieces being arranged with respect to each other for engagement at a predetermined relative position of said swingable arms, said contact pieces being rotated after engagement thereof about the axes of said arms, respectively; and torsion springs arranged inside said arms, respectively, and connected to said contact pieces, respectively, so as to oppose the rotation of said contact pieces after engagement thereof.

7. A disconnecting switch for high voltage installations, comprising in combination, a pair of swingable hollow arms; contact pieces connected to said arms, respectively, so as to be rotatable about the axes of said arms, said contact pieces being arranged with respect to each other for engagement at a predetermined relative position, each of said contact pieces including a pair of differently shaped contacts, said contact pieces being rotatable after engagement thereof about the axes of said arms, respectively, said differently shaped contacts describing arcs of different lengths about the axes of said arms during the rotation of said contact pieces; and torsion springs arranged inside said arms, respectively, and connected to said contact pieces, respectively, so as to oppose the rotation of said contact pieces after engagement thereof.

8. A disconnecting switch for high voltage installations, comprising in combination, a pair of swingable hollow arms; contact pieces connected to said arms, respectively, so as to be rotatable about the axes of said arms, said contact pieces being arranged with respect to each other for engagement at a predetermined relative position,

each of said contact pieces including a hook-shaped contact and a substantially rod-shaped contact having a length in the axial direction of said contact piece which is appreciably longer than the axial length of said hook-shaped contact, said contact pieces being rotatable after engagement thereof about the axes of said arms, respectively, whereby said rod-shaped contact of one of said contact pieces engages one leg of said hook-shaped contact of the other of said contact pieces, and vice versa; and torsion springs arranged inside said arms, respectively, and connected to said contact pieces, respectively, so as to oppose the rotation of said contact pieces after engagement thereof.

9. A disconnecting switch for high voltage installations, comprising in combination, a pair of swingable tubular arms; contact pieces connected to said arms, respectively, so as to be rotatable about the axes of said arms, said contact pieces being arranged with respect to each other for engagement at a predetermined relative position of said swingable arms, said contact pieces being rotated after engagement thereof about the axes of said arms, respectively; and torsion springs arranged inside said arms, respectively, and connected to said contact pieces, respectively, so as to oppose the rotation of said contact pieces after engagement thereof.

10. A disconnecting switch for high voltage installations, comprising in combination, a pair of swingable tubular arms; contact pieces connected to said arms, respectively, so as to be rotatable about the axes of said arms, said contact pieces being arranged with respect to each other for engagement at a predetermined relative position, each of said contact pieces including a pair of differently shaped contacts, said contact pieces being rotated after engagement thereof about the axes of said arms, respectively, said differently shaped contacts describing arcs of different lengths about the axes of said arms during the rotation of said contact pieces; and torsion springs arranged inside said arms, respectively, and connected to said contact pieces, respectively, so as to oppose the rotation of said contact pieces after engagement thereof.

11. A disconnecting switch for high voltage installations, comprising in combination, a pair of swingable tubular arms; contact pieces connected to said arms, respectively, so as to be rotatable about the axes of said arms, said contact pieces being arranged with respect to each other for engagement at a predetermined relative position; each of said contact pieces including a hook-shaped contact and a substantially rod-shaped contact having a length in the axial direction of said contact piece which is appreciably longer than the axial length of said hook-shaped contact, said contact pieces being rotated after engagement thereof about the axes of said arms, respectively, whereby said rod-shaped contact of one of said contact pieces engages one leg of said hook-shaped contact of the other of said contact pieces, and vice versa; and torsion springs arranged inside said arms, respectively, and connected to said contact pieces, respectively, so as to oppose the rotation of said contact pieces after engagement thereof.

12. A disconnecting switch for high voltage installations, comprising in combination, a pair of swingable tubular arms; a pair of swingable flexible current leads connected to said arms, respectively, contact pieces connected to said arms, respectively, so as to be rotatable about the

axes of said arms, said contact pieces being arranged with respect to each other for engagement at a predetermined relative position of said swingable arms, said contact pieces being rotated after engagement thereof about the axes of said arms, respectively; and torsion springs arranged inside said arms, respectively, and connected to said contact pieces, respectively, so as to oppose the rotation of said contact pieces after engagement thereof.

13. A disconnecting switch for high voltage installations, comprising in combination, a pair of swingable tubular arms; flexible current leads connected to said arms, respectively; contact pieces connected to said arms, respectively, so as to be rotatable about the axes of said arms, said contact pieces being arranged with respect to each other for engagement at a predetermined relative position, each of said contact pieces including a pair of differently shaped contacts, said contact pieces being rotated after engagement thereof about the axes of said arms, respectively, said differently shaped contacts describing arcs of different lengths about the axes of said arms during the rotation of said contact pieces; and torsion springs arranged inside said arms, respectively, and connected to said contact pieces, respectively, so as to oppose the rotation of said contact pieces after engagement thereof.

14. A disconnecting switch for high voltage installations, comprising in combination, a pair of swingable tubular arms; a pair of swingable flexible current leads; contact pieces connected to said arms, respectively, so as to be rotatable about the axes of said arms, said contact pieces being arranged with respect to each other for engagement at a predetermined relative position, each of said contact pieces including a hook-shaped contact and a substantially rod-shaped contact having a length in the axial direction of said contact piece which is appreciably longer than the axial length of said hook-shaped contact, said contact pieces being rotated after engagement thereof about the axes of said arms, respectively, whereby said rod-shaped contact of one of said contact pieces engages one leg of said hook-shaped contact of the other of said contact pieces, and vice versa; and torsion springs arranged inside said arms, respectively, and connected to said contact pieces, respectively, so as to oppose the rotation of said contact pieces after engagement thereof.

15. A disconnecting switch for high voltage installations, comprising in combination, a pair of tubular arms having longitudinal axes and being arranged for pivotal motion about parallel axes, respectively, disposed at right angles to the longitudinal axes of said tubular arms; contact pieces connected to said arms, respectively, so as to be rotatable about the axes of said arms, said contact pieces being arranged with respect to each other for engagement when said tubular arms are moved about the parallel axes, respectively, into substantial alignment with each other, said contact pieces being rotated after engagement thereof about the longitudinal axes of said arms, respectively; and torsion springs arranged inside said arms, respectively, and connected to said contact pieces, respectively, so as to oppose the rotation of said contact pieces after engagement thereof.

16. A disconnecting switch for high voltage installations, comprising in combination, a pair of tubular arms having longitudinal axes and being arranged for pivotal motion about parallel axes, respectively, disposed at right angles to the lon-

gitudinal axes of said tubular arms; contact pieces connected to said arms, respectively, so as to be rotatable about the axes of said arms, said contact pieces being arranged with respect to each other for engagement when said tubular arms are moved about the parallel axes, respectively, into substantial alignment with each other, each of said contact pieces including a pair of differently shaped contacts, said contact pieces being rotated after engagement thereof about the longitudinal axes of said arms, respectively, said differently shaped contacts describing arcs of different lengths about the longitudinal axes of said arms during the rotation of said contact pieces; and torsion springs arranged inside said arms, respectively, and connected to said contact pieces, respectively, so as to oppose the rotation of said contact pieces after engagement thereof.

17. A disconnecting switch for high voltage installations, comprising in combination, a pair of tubular arms having longitudinal axes and being arranged for pivotal motion about parallel axes, respectively, disposed at right angles to the longitudinal axes of said tubular arms; contact pieces connected to said arms, respectively, so as to be rotatable about the axes of said arms, said contact pieces being arranged with respect to each other for engagement when said tubular arms are moved about the parallel axes, respectively, into substantial alignment with each other, each of said contact pieces including a hook-shaped contact and a substantially rod-shaped contact having a length in the axial direction of said contact piece which is appreciably longer than the axial length of said hook-shaped contact, said contact pieces being rotated after engagement thereof about the longitudinal axes of said arms, respectively, whereby said rod-shaped contact of one of said contact pieces engages one leg of said hook-shaped contact of the other of said contact pieces, and vice versa; and torsion springs arranged inside said arms, respectively, and connected to said contact pieces, respectively, so as to oppose the rotation of said contact pieces after engagement thereof.

18. A disconnecting switch for high voltage installations, comprising in combination, a pair of parallel stationary members arranged at a distance apart from each other; a pair of tubular arms arranged for pivotal motion about said parallel stationary members, respectively; a pair of ball bearings connecting said stationary members and said tubular arms, respectively; contact pieces connected to said arms, respectively, so as to be rotatable about the axes of said arms, said contact pieces being arranged with respect to each other for engagement when said tubular arms are moved about said stationary members, respectively, into substantial alignment with each other, said contact pieces being rotated after engagement thereof about the axes of said arms, respectively; and torsion springs arranged inside said arms, respectively, and connected to said contact pieces, respectively, so as to oppose the rotation of said contact pieces after engagement thereof.

19. A disconnecting switch for high voltage installations, comprising in combination, a pair of parallel stationary members arranged at a distance apart from each other; a pair of tubular arms arranged for pivotal motion about said parallel stationary members, respectively; a pair of ball bearings connecting said stationary members and said tubular arms, respectively, contact pieces connected to said arms, respectively, so as

to be rotatable about the axes of said arms, said contact pieces being arranged with respect to each other for engagement when said tubular arms are moved about said stationary members, respectively, into substantial alignment with each other, each of said contact pieces including a pair of differently shaped contacts, said contact pieces being rotated after engagement thereof about the axes of said arms, respectively, said differently shaped contacts describing arcs of different lengths about the axes of said arms during the rotation of said contact pieces; and torsion springs arranged inside said arms, respectively, and connected to said contact pieces, respectively, so as to oppose the rotation of said contact pieces after engagement thereof.

20. A disconnecting switch for high voltage installations, comprising in combination, a pair of parallel stationary members arranged at a distance apart from each other; a pair of tubular arms arranged for pivotal motion about said parallel stationary members, respectively; a pair of ball bearings connecting said stationary members and said tubular arms, respectively; contact

pieces connected to said arms, respectively, so as to be rotatable about the axes of said arms, said contact pieces being arranged with respect to each other for engagement when said tubular arms are moved about the axes thereof, respectively, into substantial alignment with each other, each of said contact pieces including a hook-shaped contact and a substantially rod-shaped contact having a length in the axial direction of said contact piece which is appreciably longer than the axial length of said hook-shaped contact, said contact pieces being rotated after engagement thereof about the axes of said arms, respectively, whereby said rod-shaped contact of one of said contact pieces engages one leg of said hook-shaped contact of the other of said contact pieces, and vice versa; and torsion springs arranged inside said arms, respectively, and connected to said contact pieces, respectively, so as to oppose the rotation of said contact pieces after engagement thereof.
